FLUID SYSTEM INLET

Eugene L. Kilbourn, Marshall, Mich., assignor to
Progressive Dynamics, Inc., Marshall, Mich.

Filed Apr. 7, 1966, Ser. No. 1,802

Term of patent 14 years

(Cl. D91—3)

FIG. 1 is a front, elevational view of a fluid system inlet in accord with the invention.

FIG. 2 is a left side elevation thereof, the right side being similar thereto.

FIG. 3 is a plan view thereof,

FIG. 4 is a bottom view thereof, and

FIG. 5 is a rear, elevational thereof.

The dominant features of my design reside in the portions shown in full lines.

I claim:

The ornamental design for a fluid system inlet, as shown and described.
